UNITED STATES PATENT OFFICE

JOSEPH A. SHOEMAKER, OF BENNINGTON, VERMONT

DRYING DEVICE

Application filed February 14, 1929. Serial No. 339,829.

This invention relates to clothes drying devices and in particular to one that may be moved to an initial position in order to place the clothes thereon and may then be elevated 5 to a point near the ceiling in a room to take advantage of the warmer air near the ceiling of a room.

A particular object of the invention is to provide in a device of the character referred 10 to, a plurality of clothes holding arms which may be retained in their horizontal position when used for the purpose of drying clothes and which, when not in use may be dropped to a vertical position so that they are out of 15 the way.

Another important object of my invention is to provide a clothes drying device which is mounted for sliding movement upon a slide strip, means being included in the construction for elevating the clothes drying device to any desired height and frictionally holding the same at the selected point.

My preferred construction employs a series of links for holding slotted arms in their 25 horizontal position, the ends of the arms being maintained in their horizontal position through the medium of a suitable shouldered block in connection with which they are pivoted so that one or all of the arms may be used 30 at a time, depending upon the amount of material to be dried.

To enable others skilled in the art to fully comprehend the underlying features of my invention that they may embody the same in 35 the various modifications in structure and relation contemplated, a drawing depicting a preferred form has been annexed as a part of this disclosure and in such drawing, similar reference characters denote corresponding 40 parts throughout all the views, of which,

Figure 1 is a view in perspective of my improved clothes drying device showing its position in full lines near the ceiling and in outline at the lowered position at which point, 45 the clothes may be conveniently hung thereon.

Figure 2 is a view in sectional elevation of the drying device, the section being taken through the slide and through the arm holding block to illustrate how the slotted arm

may be let down to vertical position so that a minimum of space is occupied by the device when the same is not in use, and

Figure 3 is a section taken on the line 3—3 of Figure 2 illustrating the use of a U-shaped holding strip to which is secured the article holding arm through the medium of suitable links.

Referring to the drawings in detail, 5 indicates the wall of a room adjacent a window 6 at which point it is deemed most advantageous to place my clothes drying device. In order to mount the same upon the wall, use is made of a slide strip 7 which is secured to the wall in any suitable manner such as by 65 the screws 8. The edges of the slide strip 7 are flanged and are arranged to fit within the overturned edges 9 of a slide plate 10. This slide plate 10 is preferably made of 70 metal and is arranged for free sliding movement longitudinally of the slide strip 7.

To the slide plate there is secured a suitable base 11 to which in turn is secured a semi-circular block 12 provided with the radial 75 grooves 13. This block has passing therethrough a U-shaped holding strip 14 which provides a pivot point for the links 15, the links being disposed in the slots 13 and being arranged at their lower or outer end to be disposed within the slotted ends 16 of the 80 clothes holding arms 17. The ends of the holding strip 14 are inturned as at 18 and together with the upper end of an operating rod 19, are held securely between the base 11 and the slide plate 9. The plate, the base and 85 the block being secured together in any suitable manner.

It will be particularly noted that the block 12 is provided in its lower edge with a circumferential shoulder 20 and as illustrated 90 in Figure 2, this shoulder is arranged for the reception of the ends 21 of the arms 17.

In the position illustrated in Figure 2, the links 15 hold the arms loosely hanging in 95 vertical position so that they are arranged in a semi-circular fashion in alignment with their holding block 12. They are thus nested, as it were, and provide a compact structure when not in use. When, however, it is desired to place them in use, the finger piece 190

22 on the lower end of the rod 19 may be drawn down if the block 12 is in its raised position after the lock tongue 23 is moved up and when the block 12 has been lowered, the arms may be drawn out and their ends 5 21 placed beneath or within the shoulder 20 so that they are disposed in horizontal position and are ready to receive the clothes to be dried.

10 The resilient lock tongue is made of spring metal preferably and is provided with any suitable opening to provide passage for the rod 19 therethrough. Being of a resilient nature, however, and having a normal tendency to spring downwardly, this lock tongue 23 will flex the rod 19 and will also frictionally hold it against vertical movement until said tongue is raised so that the edges of the opening permit free sliding movement of the rod 19. This construction is well known as regards this particular means of locking a rod but in the use of a locking tongue that moves up, the hand can be held on the rod 19 and one of the fingers may be used to raise the tongue 23 to free the rod 19, the hand being used to allow the rod 19 to drop and stop at any convenient point.

15 It is quite evident therefore, that I have provided a neat appearing, compact clothes dryer which may be lowered to receive the clothes to be dried and may be elevated with a minimum of effort and time to a position adjacent the ceiling.

20 My improved construction, while providing a compact type of dryer also provides one which is neat in appearance, strong and durable and one in which one or more of the arms may be used at a time depending upon the requirements.

25 It is also evident that when the dryer is not in use, its arms need not be held in their horizontal position but may be readily drawn out and through the medium of the movement afforded by the link 15 may be dropped to the vertical position shown in Figure 2 to provide a neat appearing structure.

30 It is also evident that my improved drying device is out of the way when in raised position if the arms are extended and it is also out of the way when in lowered position if the arms are in their vertical position.

35 While I have illustrated and described my invention with some degree of particularity, I realize that in practice various alterations therein may be made. I therefore reserve the right and privilege of changing the form of the details of construction or otherwise altering the arrangement of the correlated parts without departing from the spirit of 40 the invention or the scope of the appended claims.

45 Having thus described my invention what I claim as new and desire to secure by United States Letters Patent is:—

50 1. A device for use in drying, comprising

55 a slide strip, a base slideable thereon, a semi-circular block secured to the base and having radial slots and a circumferential shoulder adjacent the lower ends of said slots, a U-shaped holding strip in the block passing through said slots, links pivoted to said holding strip, depending clothes holding arms pivoted to the links, said arms at the link ends being adapted for engagement with the shoulder to be supported horizontally, an operating rod depending from said base, and a yieldable rod holding member on the slide strip.

60 2. A device for use in drying comprising a slide strip, a slide plate, a base secured to said slide plate, a semi-circular block secured to said slide plate, a semi-circular block secured to the base and having radial slots and a circumferential shoulder adjacent the lower ends of said slot, a U-shaped holding strip in the block passing through said slots and having its ends imprisoned between the base and the slide plate, links pivoted to said holding strip, depending clothes holding arms pivoted to the links, said arms at the link ends being adapted for engagement with the shoulder to be supported horizontally, an operating rod depending from said base, and a yieldable rod holding member on the slide strip.

65 In testimony whereof I affix my signature. 95
JOSEPH A. SHOEMAKER. [L. S.]
